FIG. 3.

UNITED STATES PATENT OFFICE.

ERICH BUEHLE, OF NEW YORK, N. Y., ASSIGNOR TO THE PELTON WATER WHEEL CO., INC., OF SAN FRANCISCO, CALIFORNIA, A CORPORATION OF CALIFORNIA.

PRESSURE-TURBINE.

1,137,948.

Specification of Letters Patent.

Patented May 4, 1915.

Application filed June 6, 1914. Serial No. 843,507.

To all whom it may concern:

Be it known that I, ERICH BUEHLE, a subject of the Emperor of Germany, residing at New York, county of New York, 5 State of New York, have invented certain new and useful Improvements in Pressure-Turbines, of which the following is a specification.

This invention relates to hydraulic turbines, and more particularly to certain features of construction which are especially adapted for turbines of large size and whereby certain difficulties which have been heretofore experienced are eliminated.

15 One of the objects of the invention is to provide a running joint between the runner and casing in which no packing is used and in coöperation with which an annular chamber is provided for the purpose of receiving 20 the leakage through the joint, means being also provided for rapidly conveying this leakage away from the chamber.

A further object is to provide means for reducing the pressure on the top of the runner of a horizontal turbine so as to relieve the thrust bearing of a certain amount of load which it would otherwise have.

A further object is to provide the upper wall of a horizontal runner with openings 30 which cause the runner to act as a pump to withdraw water from the upper side of the runner and also produce a vacuum in the space above the runner in excess of the vacuum in the draft tube.

35 A further object is to provide an oil reservoir around the vertical shaft of a horizontal turbine which receives the oil from the lower shaft bearing, and also to provide means for preventing water from flowing 40 upwardly along the shaft and escaping into the oil reservoir.

A further object is to provide a simple and inexpensive mounting for the gate operating ring which will permit the parts 45 to be readily assembled and disassembled.

A further object is to provide the turbine casing with hollow guide vanes through which water which leaks through the joint between the runner and the casing may be 50 conducted to the draft tube.

A further object is to provide means whereby the suction in the draft tube is utilized for withdrawing the leakage water from

above the joint between the runner and the casing.

Other objects and the features of novelty will appear in the following description taken in connection with the accompanying drawings, in which,

Figure 1 is a vertical section through a 60 hydraulic turbine embodying my invention, the turbine being shown as direct-connected to an electric generator; Fig. 2 is an enlarged section similar to Fig. 1, but showing only a portion of the apparatus; Fig. 3 is 65 a vertical section of a modified form of certain parts shown in Fig. 1; Fig. 4 is a vertical section through the openings in the upper wall of the runner; and Fig. 5 is a section on the line 5—5 of Fig. 2.

Referring to the drawings, 10 indicates the usual foundation which supports the apparatus. The draft tube 11 is arranged in the foundation 10 and has connected therewith the supply casing or scroll 12 on which is secured a housing 13 which supports a part of the electric generator 14. A vertical shaft 16 carries at its lower end a runner 17 which is arranged in the scroll 12 and is provided with the usual vanes 18. Arranged within the scroll 12 and, if preferred, formed integral therewith are the wearing rings or plates 19 between which are the usual wicket gates 20. The upper and lower walls of the casing or scroll 12 are connected 85 by the usual guide vanes 21 and where the size of the apparatus permits these vanes have openings 22 extending therethrough for a purpose to be hereinafter described.

The runner 17 has its peripheral portions 90 arranged to coöperate with the wearing plates 19 to form running joints 23 and 24. The vertical wall 25 of the runner which connects the lower ends of the vanes thereof is spaced from the wall of the casing to 95 provide a channel 26 which communicates at its lower end with the interior of the draft tube 11. The joint 23 communicates with the channel 26 and therefore any leakage of the pressure water through the joint 23 will be conveyed to the draft tube by the channel 26. The runner is provided with an upstanding peripheral flange 27 which is arranged between the upper plate 19 and a depending flange 28 on the casing, the plate 19 coöoperating with the outer surface of the

flange 27 to form the joint 24 and the flange 28 coöperating with the inner surface of the flange 27 to form the joint 29. The casting comprises a cover plate 30 having an annular chamber 31 in the lower side thereof and in communication with the upper ends of the joints 24 and 29. One or more passages 32 are formed in the plate 30 for conveying water which escapes into the chamber 31 to the passages 22 through the guide vanes 21. From the lower end of the passages 22 the water is conveyed through pipes 33 to the draft tube 11.

In the normal operation of the apparatus there is a partial vacuum in the draft tube 11 and therefore there is constant suction in the passages 32 and the chamber 31, this suction drawing the water from the joint 24 through the passages into the draft tube.

Under all ordinary conditions of operation this suction is sufficient to carry off all leakage through the joint 24, but under certain abnormal conditions of operation an excess of water may accumulate in the chamber 31 and pass through the joint 29 into the chamber on the upper side of the runner 17. The action of the water in passing through the runner together with the weight of the runner, the shaft and the rotating part of the electric generator produces a very great vertical thrust on the shaft and this thrust must be taken up by the usual thrust bearing. It is obvious that if water were allowed to accumulate on the upper side of the runner and thus exert downward pressure thereon this would increase the load on the thrust bearing and also lower the efficiency of the apparatus. It is therefore desirable to provide means for preventing the accumulation of water on the runner, as far as possible, and also to have a vacuum on the upper side of the runner which will relieve the thrust bearing of a certain amount of its load and in this way improve the efficiency of the apparatus. The suction in the draft tube acts through the passages 22, 32 and the joint 29 to produce a vacuum in the chamber 34 above the runner, but in order to further increase the vacuum on the upper side of the runner and to make it exceed that in the draft tube I have provided a series of openings 35 in the upper wall of the runner, these openings being inclined upwardly in the direction of rotation of the runner, as clearly shown in Fig. 4. With the openings 35 thus arranged, the upper wall of the runner serves as an impeller to withdraw water and air from the chamber 34 and thus reduce pressure in this chamber to a point below that in the draft tube into which the openings 35 discharge.

The central part of the cover 30 is so formed as to provide a reservoir 36 for oil and within the inner wall 37 of this reservoir there is formed an annular chamber 38,

the inner wall 39 of which makes a running joint with the shaft 16. The hub 40 of the runner 17 makes a running joint 41 with the lower wall of the reservoir 36.

The shaft 16 has a bearing 42 in a member 43 which is mounted on the plate 30. Oil from the bearing 42 descends along the shaft and is discharged into the reservoir 36 by means of a deflecting flange 44 which is carried by the shaft. The chamber 38 has a cover 45 which receives the oil from the deflecting flange 44 and conveys it to the reservoir 36, this cover also preventing oil from entering the chamber 38.

It sometimes occurs in the operation of apparatus of this character that abnormal fluctuations in the load on a generator would cause the upper side of the runner to be flooded with water and this water would be forced upwardly through the joint 40 and also the joint between the shaft 16 and the wall 39 of the chamber 38. It will be seen from the drawings that if the water were allowed to continue its upward movement to the oil deflecting means 44 it would get into the oil reservoir 36. In order to prevent this, I have provided on the shaft 16 a deflector 46 below the deflector 44. The deflector 46 operates to turn any water which is thrown against it back into the chamber 38 whence it escapes through the passage 47. The arrangement of the deflectors 44 and 46 is such that oil is prevented from getting into the chamber 38 and water is prevented from getting into the reservoir 36, so that these two fluids are always kept separate.

The bearings for the shaft 16 are preferably supplied with oil by means of a pump 48 which is directly driven from the shaft 16 by means of the gears 49, these gears also driving a shaft 50 which actuates the governing mechanism 51, the latter forming no part of the present invention and a description thereof being unessential. Oil may be supplied to the bearing 42 and the gears 49 in any suitable manner, as by means of the pipes 52 and 53, respectively.

The wicket gates 20 are arranged on shafts or pivots 54 having arms 55 at their upper ends, these arms being operatively connected with an oscillatable ring 56 which is mounted on a bearing 57 on the plate 30. This plate is also provided with a shoulder 58 which supports the ring. The member 43 which is secured on the upper end of the plate 30 has a laterally projecting flange 59 which overlies a portion of the ring 56 and coöperates with the shoulder 58 to hold the ring in position. This manner of mounting the ring 56 is obviously very simple in construction and permits the parts to be readily disassembled because when the member 43 is removed the ring may be lifted from the plate 30. In order to control the position of all of the gates 20 simultaneously the ring 130

56 is oscillated by means of any suitable mechanism which may be connected with the ring by means of a pin 60.

6 In the drawings the running and stationary parts of the apparatus are shown much farther apart at the running joints than they would be in practice, and this has been because to show the spaces in the joints in the exact proportion to the other parts 10 would make the spaces so small as to obscure the arrangement.

In Fig. 3 I have shown a modification of the invention in which the shaft 16^a is provided with a flange 61 at the lower end 15 thereof to which the runner 17^a is secured. The plate 30^a is provided with the oil reservoir 36^a, as in the form hereinbefore described, but the lower wall 62 of the reservoir makes a running joint with the periphery of the flange 61. There is provided within the reservoir 36^a a water chamber 38^a, the inner wall of which is provided with an annular recess 63 and co-operates with the shaft 16^a to form a running joint. The recess 63 has connected therewith a pipe 64 which is in turn connected with a suitable suction pipe for withdrawing water from the recess 63. The pipe 64 is preferably connected with the draft tube so that 20 the water is withdrawn from the recess 63 and discharged into the draft tube.

Arranged on the shaft 16^a is a deflector 65 which throws oil into the chamber 36^a and has its lower end 66 cupped out to form a 35 deflector for water which is forced upwardly along the shaft above the recess 63. The cupped end 66 of the deflector 65 throws the water back into the chamber 38^a from which it escapes by means of the passage 67.

40 Referring to Fig. 1, it will be seen that there is indicated in dotted lines the pipe 68 extending from the passage 32 to the connection of the pipe 33 with the draft tube 11. When the size of the apparatus is such that 45 it is impracticable to provide hollow vanes 22 a pipe or pipes 68 may be provided to convey the water from the chamber 31 to the draft tube.

Having thus described the invention, what 50 is claimed and desired to be secured by Letters Patent is:

1. In apparatus of the class described, the combination of a runner, a casing inclosing the runner and forming with the back of 55 the runner a plurality of annular chambers, said casing having a running joint with the periphery of the runner communicating with one of said chambers, and suction means communicating with both of said 60 chambers.

2. In apparatus of the class described, the combination of a runner, a casing inclosing the runner and forming with the back of 65 the runner a plurality of annular chambers, said casing having a running joint with the

periphery of the runner communicating with one of said chambers, a draft tube adapted to receive the water discharged from said runner, and means for establishing communication between said draft tube 70 and both of said chambers.

3. In apparatus of the class described, the combination of a runner, a casing inclosing the runner and having spaced parts co-operating respectively with the opposite 75 sides of a peripheral flange on said runner and forming running joints therewith, said casing having an annular chamber communicating directly with both of said joints, and suction means communicating with said 80 chamber.

4. In apparatus of the class described, the combination of a runner having a vertical axis and an upstanding peripheral flange, a casing inclosing said runner and having parts co-operating with the inner and outer sides of said flange to form running joints therewith, said casing forming with the runner two annular chambers separated by the 85 inner of said parts which co-operates with the inner side of said flange, a draft tube, a conduit establishing communication between the outer of said chambers and said draft tube and said runner having openings in the upper wall thereof establishing communication between the inner of said chambers and the draft tube.

5. In apparatus of the class described, the combination of a runner having a vertical axis and an upstanding peripheral flange, a casing inclosing said runner and having parts co-operating with the inner and outer sides of said flange to form running joints therewith, said casing forming with the runner two concentric annular chambers, the outer of which communicates with both of 100 said joints and the inner of which communicates only with the inner of said joints, and suction means communicating with both of 105 said chambers and adapted to withdraw water therefrom.

6. In apparatus of the class described, the combination of a vertical shaft, a runner mounted on said shaft, a casing inclosing said runner and provided with an oil reservoir above the runner and surrounding said shaft, said casing also having an annular water chamber within said oil reservoir, the inner wall of said chamber co-operating with said shaft to form a running joint therewith, and means carried by the shaft 115 for receiving water, forced upwardly through said joint, and deflecting the water into said chamber whereby the water is prevented from getting into said reservoir.

7. In apparatus of the class described, the combination of a vertical shaft, a runner mounted on said shaft, a casing inclosing said runner and provided with a bearing for 120 said shaft above the runner and an oil res-

- ervoir surrounding said shaft above the runner and below said bearing, deflecting means carried by the shaft below said bearing and adapted to discharge oil, flowing 5 downwardly along said shaft, into said reservoir, said casing also being provided with a chamber surrounding said shaft within said reservoir, the inner wall of said chamber having a running joint with said shaft, 10 and means above said joint and below said deflecting means for deflecting water, which is forced upwardly along said shaft, into said chamber and thereby preventing the water from getting into said reservoir.
- 15 8. In apparatus of the class described, the combination of a vertical shaft, a runner mounted on the lower end of said shaft, a casing inclosing said runner and having a bearing for said shaft and an oil reservoir 20 arranged above the runner and below said bearing, deflecting means carried by the shaft below said bearing and adapted to discharge oil, flowing downwardly along said shaft, into said reservoir, said casing being 25 also provided with a chamber within said reservoir and below said deflecting means to receive water, which is forced upwardly along said shaft, and separate means for withdrawing the water from said chamber 30 and the oil from said reservoir.
9. In apparatus of the class described, the combination of a runner having a vertical axis, a casing inclosing said runner and having a chamber above the runner, a draft 35 tube below the runner and the upper wall of the runner having openings formed therein inclined upwardly in the direction of rotation of the runner whereby the upper wall of the runner is adapted to act as a pump 40 to withdraw water from the upper side of the runner and produce a vacuum in said chamber which is greater than the vacuum in the draft tube.
10. In apparatus of the class described, the combination of a vertical shaft, a runner mounted thereon, a horizontally arranged casing for the runner provided with a chamber on the upper side of the runner, the upper wall of the runner having openings therein inclined upwardly in the direction of rotation of the runner, as and for the purpose described. 45
11. In apparatus of the class described, the combination of a runner, a casing for the runner and having a part coöperating with the periphery of the runner to form a running joint therebetween, said casing also having an annular chamber above said joint and in communication therewith, hollow strengthening ribs extending across said 50 casing and conduits connecting said chamber with said ribs to convey the water, which leaks through said joint, through said ribs. 55
12. In apparatus of the class described, the combination of a vertical shaft, a runner secured to said shaft, a casing inclosing said runner and having an oil reservoir surrounding the shaft above the runner, said casing being also provided with a plurality of coaxial chambers surrounding the shaft 60 within said reservoir, and drainage means connected with said chambers and adapted to withdraw water therefrom. 65
